(Cl. D54—13)

To all whom it may concern:

Be it known that I, Albert Henry Hawes, a subject of the King of Great Britain, residing at Erdington, Birmingham, county of Warwick, England, have invented a new, original, and ornamental Design for a Combined Hammer, Spanner, Tommy Bar, and Crowbar, of which the following is a specification, reference being had to the accompanying drawing, forming part thereof.

The figure is a perspective view of a combined hammer, spanner, tommy bar, and crowbar embodying my new design.

I claim:

The ornamental design for a combined ham-
mer, spanner, tommy bar, and crowbar, as shown.

ALBERT HENRY HAWES.
